UNITED STATES PATENT OFFICE.

LOUIS SCHUTTE, OF PHILADELPHIA, PENNSYLVANIA.

DEVICE FOR OPERATING VALVES AND OTHER MECHANISMS.

SPECIFICATION forming part of Letters Patent No. 380,941, dated April 10, 1888.

Application filed June 11, 1887. Serial No. 241,038. (No model.)

To all whom it may concern:

Be it known that I, LOUIS SCHUTTE, of Philadelphia, in the county of Philadelphia and State of Pennsylvania, have invented certain 5 Improvements in Devices for Operating Valves and other Mechanisms, of which the following is a specification.

The object of the present invention is to convert prolonged or continuing reciprocations 10 into sudden or instantaneous reciprocations, &c.

My invention is applicable in many places which will suggest themselves to the skilled 15 mechanic, but is specially advantageous as a means of effecting a sudden opening and closing of valves which are controlled by floats having a gradual rising and falling motion, and I have therefore illustrated the same in such connection.

20 In the accompanying drawings, Figure 1 represents a side elevation of an ordinary injector or jet apparatus with my device applied thereto. Fig. 2 represents a vertical axial section through the valve-spindle and the parts immediately connected therewith. Fig. 3 is an 25 end elevation of said parts. Fig. 4 is a section showing the valve-operating devices in a reverse position.

Referring to the drawings, A represents the 30 controlling valve-spindle of an ordinary injector, which opens and closes the passage B by a longitudinal movement. This spindle is extended through a gland or stuffing-box to the exterior of the apparatus and connected by 35 horizontal pivots *a* to the two arms of a U-shaped lever, B', which vibrates around a horizontal pivot, *b*, located at its lower end and sustained in stationary cheek-plates C, secured to or formed on the body of the injector. The 40 swinging motion of this lever has the effect of opening or closing the valve.

D represents a second forked lever, mounted at its lower end on the horizontal pivot *c*, which is also sustained in the stationary cheek-plates 45 C, before referred to.

E represents a strong spiral spring, which is seated at its lower end in a socket, *d*, pivoted to the top of the lever B', and seated at its upper end in a socket, *e*, pivoted to the top of the lever D.

50 As the lever D is turned upon its pivot *c*, it carries the upper end of the spring E forward

and backward, so that the spring will tend to push the lever B' in one direction or the other, according to the position of the lever D. From 55 the lever D a rod, F, is extended downward to a lever, G, pivoted to a stationary support and provided with a float, H, which will be located in a boiler, reservoir, or other fluid receptacle. As the fluid level rises, it lifts the float, which, 60 through the intermediate parts, turns the lever D to the position shown in Figs. 1 and 2, whereupon the spring acts to throw the lever B' outward, as indicated by the arrow in Fig. 2, thereby opening the valve. When, on the 65 contrary, the fluid level falls, the float descends, and the lever D, tipping forward, places the spring in the position shown in Fig. 4, so that it acts to return the lever B' to its original position and close the valve. The spring 70 reverses its action upon the lever B as its upper end is carried to one side or the other of a vertical line falling through the pivot *b*. When the spring is carried to one side or the other of this line, it acts to move the valve very suddenly, and thus it is that the gradual or continued motion of the float is caused to effect an 75 instantaneous opening or closing of the valve at the proper time.

By giving the end of the valve-spindle or 80 valve proper a sectional area considerably greater than that of the spindle proper, the sudden opening and closing motion is rendered the more certain, since the pressure of the fluid being controlled will tend to urge the 85 valve in one direction or the other as the relative pressures on its front and rear sides are varied by the opening and closing action.

While I prefer to make use of the spiral 90 spring, it is to be understood that any equivalent form of compression-spring may be employed.

In the use of steam-injectors, particularly for boiler-feeding purposes, it is of importance that the actuating jet of steam shall be stopped 95 and started instantly and to its full extent. This is desirable in order to prevent reverse currents through the apparatus and to enable the steam-jet to initiate the currents in the required direction against the counter-pressure 100 of the boiler. Heretofore, so far as I am aware, no one has combined with a steam-injector automatic devices for effecting this instantaneous opening and closing of the steam-control-

ling valve, and it is in this combination that my device for converting motion is of special importance. As regards the particular mechanism which I have selected for representation 5 in the drawings, it will be observed that it consists of two independently-pivoted levers, one of which is connected to and arranged to directly operate the valve-spindle, while the other serves solely to change the inclination 10 or angle of the spindle-operating spring.

I am aware that various contrivances containing springs and weights have been devised for imparting from a slowly-moving part a sudden movement to a valve; but I believe 15 myself to be the first to devise the particular combination herein shown for that purpose and broadly the first to combine with the steam-controlling valve of an injector automatic devices for suddenly changing its position. 20

Having thus described my invention, what I claim is—

1. In combination with the steam-admission valve of a steam-injector, a float, a lever connected with and operated by said float, and a spring located between the lever and valve, said spring acting at one end on the valve to move the same and movable at the opposite end with the lever, substantially as described, 25 whereby the slowly-moving float is enabled to effect the opening and closing of the injector with an instantaneous action, thereby avoiding the waste of steam and insuring the proper 30 action of the injector.

2. The injector-body provided with the rigid 35 cheek-plates, in combination with the valve-spindle, the forked lever B, pivoted between the cheek-plates straddling the spindle and connected to the latter by pivots, the forked lever D, also pivoted to the cheek-plates, the 40 spring seated between and against the two levers, and the float connected to lever D.

3. The spindle and its operating-lever B, provided with the pivoted spring-bearing d, in combination with the independently-pivoted lever D, having the bearing e, pivoted thereto, and the compression-spring seated between and against said bearings d e. 45

4. A reciprocating spindle, a lever pivoted thereto, and a compression-spring bearing at 50 one end on said lever to move the spindle endwise, in combination with a second and independent lever bearing on the opposite end of the spring and arranged, as described, to change the angle or inclination of the spring 55 in respect to the first-named lever, whereby the spring and first lever are enabled to move independently of the second lever and throw the valve suddenly first in one direction and then in the other. 60

In testimony whereof I hereunto set my hand, this 16th day of May, 1887, in the presence of two attesting witnesses.

LOUIS SCHUTTE.
